UNITED STATES PATENT OFFICE.

ALEXANDER M. KERR, OF DETROIT, MICHIGAN, ASSIGNOR OF ONE-HALF
TO HERBERT H. HEWITT, OF BUFFALO, NEW YORK.

JOURNAL-BEARING.

SPECIFICATION forming part of Letters Patent No. 722,427, dated March 10, 1903.

Application filed September 11, 1902. Serial No. 122,918. (No model.)

To all whom it may concern:

Be it known that I, ALEXANDER M. KERR, a citizen of the United States, residing at Detroit, county of Wayne, State of Michigan, 5 have invented a certain new and useful Improvement in Journal-Bearings; and I declare the following to be a full, clear, and exact description of the invention, such as will enable others skilled in the art to which it 10 pertains to make and use the same, reference being had to the accompanying drawings, which form a part of this specification.

My invention relates to an improvement in journal-bearings shown in the accompanying 15 drawings and more particularly set forth in the following specification and claims.

In the drawings, Figure 1 is a vertical longitudinal section through the bearing, the equalizing-plate, and key. Fig. 2 is a cross- 20 sectional view through the same. Fig. 3 is a plan view of the equalizer. Fig. 4 is a longitudinal section through the journal-bearing.

One object of my invention is to provide 25 means to lessen the shoulder-pressure of the journal on the bearing, which is well known to be largely the cause of heating the journal due to the end thrust on the bearing.

Another object of my invention is to provide means for equalizing the pressure be- 30 tween the bearing and the key, so as to insure the face of the bearing having an equal bearing the whole length of the journal, thereby relieving any unequal pressure be- 35 tween the parts, notwithstanding a variation in the angle of the journal.

Referring to the letters of reference shown 40 on the drawings, A is the journal and B the brass or bearing provided on its upper side with a concave, convex, or wedge shape sur- face.

B' is the Babbitt or antifriction metal com- monly employed on the face of the brass.

C is an equalizing-plate, its upper and lower 45 surfaces being concave, convex, or wedge shape to conform to the opposing faces of the bearing B and the key D.

d represents lugs cast integral with the key, and c c are ears formed on each side of the equalizing-plate and provided with elong- 50 gated slots c', through which the lugs d pass.

These lugs are then rivet-headed for the purpose of loosely engaging the equalizing-plate with the key. By permitting lateral movement between the bearing, equalizing-plate, and key the tendency to heat the journal, due 55 to the shoulder-pressure of the axle on the end of the bearing, is reduced to the minimum.

The operation of the parts will be readily understood. When the movement of the car causes a variation in the angle of the journal, 60 the pressure of the bearing on the equalizing-plate at one end moves the equalizing-plate laterally, crowding it into a position where the pressure between the journal and the key is equal. It is of course apparent that like 65 results will be obtained whether the upper surface of the bearing and the complementary parts are either concave, convex, or in the form of a double wedge, and I would have it distinctly understood that I contem- 70 plate the employment of either the suggested forms. The curvature or angle may be more or less as the requirements of the case demand. The greater the curvature or angle the less travel required. It will also be no- 75 ticed that the lateral motion provided between the parts compensates for any defective alignment found between the axle-box and journal.

While I have described my invention for convenience as a car-axle bearing, it is ap- 80 parent that it is equally well adapted for any journal-bearing in which the nature of its employment makes it advantageous to provide means for equalizing the pressure between the journal-bearing and adjacent 85 parts.

Having thus described my invention, what I claim is—

1. The combination of a brass, a key pro- 90 vided on each side with depending lugs adapted to loosely engage a filling-piece interposed between the brass and key, and the filling-piece provided with ears having elongated slots to receive the depending lugs, the construction being such that said filling- 95 piece is free to move endwise to equalize the pressure on the several parts, substantially as described.

2. In a journal-bearing, the combination of 100 a brass having a convex upper face, a key

having a convex lower face, and a filling-
piece interposed between the brass and key,
its faces being complementary to those of
the brass and key, the construction being
5 such as to adapt it to move endwise to equal-
ize the pressure on the several parts, sub-
stantially as described.

In testimony whereof I sign this specifica-
tion in the presence of two witnesses.

ALEXANDER M. KERR.
